UNITED STATES PATENT OFFICE.

EDUARD RUBIN, OF THUN, SWITZERLAND.

BARREL FOR FIRE-ARMS.

SPECIFICATION forming part of Letters Patent No. 338,192, dated March 16, 1886.

Application filed June 14, 1884. Renewed January 11, 1886. Serial No. 188,287. (Model.)

To all whom it may concern:

Be it known that I, EDUARD RUBIN, of Thun, in the Republic of Switzerland, have invented certain new and useful Improvements 5 in Barrels for Fire-Arms, of which the following is a specification.

My invention relates to improvements in rifle-barrels; and it consists of a barrel having grooves vanishing at their rear ends into a 10 smooth portion of the same diameter, which forms the front part of the cartridge-chamber.

The diameter of the cartridge-chamber is larger than that of the rifled portion of the barrel and connected therewith by an intermediate conical 15 and a short cylindrical portion.

In the accompanying drawings, Figure 1 is a vertical longitudinal section of a rifle-barrel embodying my invention; and Figs. 2 and 3 are vertical transverse sections, respectively, 20 on lines $x x$ and $y y$, Fig. 1.

Similar letters of reference indicate corresponding parts.

The barrel A is by preference made of cast-steel and of the usual internal dimensions, and 25 may be used in connection with any approved breech closing and repeating mechanism. The bore has a diameter of from seven and fifteen-tenths millimeters to eight millimeters, and is provided with from three to six grooves, 30 $a a$, of a depth of 0.15 millimeters. The width of the grooves and the intermediate spaces are equal to each other. The grooves $a a$ make one turn for a length of two hundred and seventy to three hundred millimeters.

35 The grooves $a a$ vanish at their rear ends, as shown at b in the drawings, into a smooth rear end, d^1 , of the rifled portion, which has the same diameter as the rifled portion, and which forms the front part of the cartridge-chamber 40 B. The twist of the grooves may be uniform or gaining.

It will be evident that rifle-barrels in which the rifles gradually vanish at their rear ends can be more readily cleaned.

The cartridge-chamber B consists of a main 45 part of cylindrical shape, a conical part, d^1 , a short cylindrical part, d^2 , and the smooth cylindrical rear end, d^3 , of the rifled portion. A shoulder is formed between the cylindrical parts d^2 and d^3 , against which abuts the edge 50 of the shell of the cartridge. The main part d of the cartridge-chamber has a larger diameter than that of the rifled portion of the barrel A, so as to admit a comparatively large charge of powder in the cartridge. 55

The comparatively small bore of my gun (about 0.31 inch) admits the firing of long projectiles with heavy charges without serious recoil, even with light weapons. The heavy twist of the grooves imparts to the ball a very 60 considerable rotation, so as to prevent deviations from the trajectory.

To prevent the stripping off of the lead projectile by the edges of the grooves, I prefer to use cartridges the projectiles of which have a 65 copper or other sheathing—such as described in a separate application for Letters Patent filed at the same time herewith, to which reference is made.

Having thus described my invention, I claim 70 as new and desire to secure by Letters Patent—

A rifle-barrel consisting of a rifled portion, A, having grooves $a a$ gradually vanishing at their rear ends in a smooth portion, d^1 , of the same diameter as the curve of the lands of said 75 rifled portion, and of a cartridge-chamber, B, formed of an enlarged cylindrical main part, d , a short cylindrical portion, d^2 , slightly larger than and just in the rear of said portion d^3 , and a conical portion, d^4 , connecting said parts 80 d and d^2 , substantially as described.

In testimony that I claim the foregoing as my invention I have signed my name in presence of two subscribing witnesses.

ED. RUBIN.
